UNITED STATES PATENT OFFICE.

JOHN D. A. JOHNSON, OF OMAHA, NEBRASKA.

MECHANICAL MOVEMENT.

No. 861,658.

Specification of Letters Patent.

Patented July 30, 1907.

Application filed September 28, 1906. Serial No. 336,611.

To all whom it may concern:

Be it known that I, JOHN D. A. JOHNSON, a citizen of the United States, residing at Omaha, in the county of Douglas and State of Nebraska, have invented certain new and useful Improvements in Mechanical Movements, of which the following is a specification.

This invention relates to improvements in mechanical movements of the class producing a reciprocating rotary movement of a single shaft.

10 The primary object of the invention is to present a movement of this class, of few parts, which will be of simple construction, but effective used in connection with washing machines.

15 The invention has reference to the employment of a central vertical shaft adapted to have a reciprocating rotary motion from the transverse movement of a rack-bar, the latter having sprocket-chain connection to cause rotation of a balance wheel found useful.

20 The invention also includes means for operation by either machinery or hand-power, and has certain features of novelty and utility which will be more fully described hereinafter.

25 The immediate result to be attained is the rotation of the dasher or stirrer within the tub, in one direction and then in a reverse direction, from a forward and backward movement of the hand-lever.

30 In the accompanying drawings which represent the invention, Figure 1 is a perspective view of a washing machine the invention being shown mounted thereon in operative position, the figure having a broken away part to disclose the interior. Fig. 2 is a detail relating to Fig. 1, being a broken away view of the horizontal shaft and frame, introduced to show preferred construction for shaft bearings, the view looking centrally to the hand lever from the rear of the machine. Fig. 35 3 is a detail in section relating to Fig. 2. Fig. 4 is a plan view partly in section, showing formation of head of rack-bar and connecting means thereof with sprocket-chain. Fig. 5 is a plan view of the invention introduced to show location of horizontal shafts.

40 Referring now to the figures of the drawing, the numeral 1 represents a washing machine having a tub 2, for holding water and clothes to be washed, suitably sustained upon legs 3, the latter having cross-pieces 45 passed and secured near the lower ends of the legs. The tub has a cover consisting of the stationary part 5 and connected to the latter, as by hinges, is the swinging part 6; the swinging part 6 of the cover has secured upon its under side a segmental leaf 7, which is a common construction, and which permits the fastening upon the rim of the tub, of a clothes wringer. The parts thus described are old and well known features; and upon cover 6, are mounted the several parts of my invention.

55 I construct as a part of the frame employed, the plate 8 having ears 9 bolted or screwed to the cover.

This plate extends from the center of the cover horizontally to the edge, and has the angularly formed arm 10 extending below the plane of the cover, terminating in the horizontal projection 11 upon the end of which, 60 at 12, is pivotally mounted the lever 13. Vertically seated upon the head 14' of plate 8 is the pinion 14 having a vertically disposed shaft 15 rigidly secured thereon, and extended downward traversing head 14' and passing within the tub. Slidably mounted upon 65 shaft 15 is disk 16, having prongs 17 rigidly secured upon its under side. Slots 18 are formed transversely through the disk which are adapted to ride upon fins 19, which prevent said disk from having a horizontal swing independent of shaft 15.

70 Upon the rear of cover 6 and near hinges 20, upon brackets 21 and 22, as bearings, is mounted the horizontal shaft 23; and upon the outer end of shaft 23 is mounted the balance-wheel 24—shaft 23 extends in a direction transverse to plate 8 and is extended across 75 the end of the cover, and upon its inner end is mounted the sprocket-wheel 25.

Upon brackets 26' and 27 as bearings, and disposed somewhat nearer the center of cover 6, and parallel with shaft 23, is shaft 26; and upon the inner end of 80 shaft 26 is mounted the sprocket-wheel 27. The upper end of lever 13 is provided with socket 28 within which a suitable handle 29 is removably seated. I provide a rack bar 30 having teeth 31 formed on side 32 thereof, the side 34 (Fig. 4) being smooth. The outer end of 85 the rack-bar is pivotally mounted at 34' upon lever 13 and passes centrally of the cover to engage the teeth of pinion 14, being held to this engagement by means of the vertically disposed roller 35 (Figs. 4—5) and the inner end of the rack-bar is provided with the head 36 90 having the transverse projection 37.

As thus described wheels 25 and 27 are vertically disposed and occupy the same plane, said plane being parallel with and closely adjacent to the plane occupied by the rack-bar, this being an arrangement of 95 parts extending across the central part of the cover. Upon the series of teeth 38 of wheels 25 and 27 is seated the sprocket chain 39, these teeth having well known bearings between the links 40 (Fig. 4) of the chain. One of the pivots of the chain, as pivot 41, (Fig. 4) 100 formed of a length sufficient to traverse the head 36 and angular projection 37 of the rack-bar and is employed, whereby the rack-bar is pivotally secured to chain 39; and in operation, when lever 13 is moved forward and then backward in a direction toward or from the center of the cover, teeth 31 of the rack-bar engage the teeth of pinion 14 and causes shaft 15 to be rotated first in one direction and then in a reverse direction, as is evident; and the rack-bar, which is attached at its inner end 42 (Fig. 5), will cause said chain to have a 105 movement in a manner to rotate shaft 23, thereby causing rotation of the balance wheel 24.

The inner end 42 of the rack-bar, during the lengthwise movement of the bar will have an upward and downward swing, and therefore pinion 14 has a sufficient length so that its teeth will have a constant engagement with the teeth of the rack-bar; roller 35, it will be remembered has a contact with the smooth edge 34, during the movement of the bar, thereby preserving this contact.

Teeth 31, have curved upper (Fig. 4) and lower ends 10 so that they may have a smooth engagement with the teeth of pinion 14. During operation, chain 39, rides upon teeth 38 of wheel 25 and 27 in a smooth manner, and shaft 26 is employed for the single purpose of sustaining wheel 27 in an operative position.

15 It will be noted that balance wheel 24 is useful for furnishing momentum for carrying the movement of prongs 17, when the latter engage the clothing. This momentum is also depended upon to prevent any delayed movement of the end 42 of the rack bar when 20 passing the dead-center of wheels 25 and 27. A band indicated at 43 may be used upon wheel 24, such band to be actuated from any suitable source of power, and shaft 15, thereby rotated, this being a substitute for hand power.

25 During the movement of head 36 of the rack-bar, it passes closely adjacent to wheels 25 and 27; the angular projection 37 however, causes the rack-bar to be positioned at all times sufficiently adjacent so that the rack bar does not come in contact with the wheels.

30 It is an advantage as is evident to employ balls as at 44 for shafts 23 and 26, and this preferred construction is shown by Fig. 3.

I have described the use of this movement in connection with washing machines, but this movement 35 would be of utility for churning, or other machines of that class, and therefore I do not wish to be understood as limiting its use.

Having given a full description, what I claim as my invention is:—

1. In combination, a mechanical movement as described, 40 comprising a rack-bar, an idler pinion; a vertical shaft a pinion rigidly secured upon its upper end; a horizontal shaft disposed transversely with reference to the rack-bar and a balance wheel mounted upon its outer end and a pinion upon its inner end; a sprocket chain connecting the idler pinion and the pinion upon the inner end of the horizontal shaft; said rack-bar being mounted upon suitable bearings in a manner to engage the pinion upon the vertical shaft, and having its inner end secured upon 45 said sprocket chain, and means to cause a movement of the 50 rack-bar.

2. In combination, a mechanical movement as described, 55 comprising a rack-bar, an idler pinion; a vertical shaft a pinion rigidly secured upon its upper end; a horizontal shaft disposed transversely with reference to the rack-bar and a balance wheel mounted upon its outer end and a pinion upon its inner end; a flexible member connecting the idler pinion and the pinion upon the inner end of the horizontal shaft; said rack-bar being mounted upon suitable bearings in a manner to engage the pinion upon the 60 vertical shaft and having its inner end secured upon said flexible member, and means to cause a movement of said rack-bar.

3. In combination, a mechanical movement, comprising 65 a rack-bar; a vertical shaft a pinion rigidly secured upon its upper end; a horizontal shaft disposed transversely with reference to the rack-bar and a balance wheel mounted upon its outer end and a pinion upon its inner end; said rack-bar being mounted upon suitable bearings in a manner to engage the pinion upon the vertical shaft; a connection between the pinion of the horizontal shaft and the rack-bar for causing a rotary movement of the pinion of the 70 horizontal shaft from an endwise movement of the rack-bar; and means to cause an endwise movement of said rack-bar.

In testimony whereof he has affixed his signature in presence of two witnesses.

JOHN D. A. JOHNSON.
